Primary Examiner — Ania Aman(74) *Attorney, Agent, or Firm* — Brouillette Legal Inc.; Robert Brouillette(57) **CLAIM**

The ornamental design for a snow vehicle for upright use, as shown and described.

DESCRIPTION

FIG. 1 is a front, top, right perspective view of a snow vehicle for upright use;

FIG. 2 is a front elevation view thereof;

FIG. 3 is a back elevation view thereof;

FIG. 4 is a right elevation view thereof;

FIG. 5 is a left elevation view thereof; and,

FIG. 6 is a top plan view thereof.

The broken lines shown on the drawings depict portions of snow vehicle for upright use that form no part of the claimed design.
